UNITED STATES PATENT OFFICE.

FRANK THILL, OF LONG ISLAND CITY, NEW YORK.

WINDOW-SEAL STRIP.

Application filed April 7, 1925. Serial No. 21,354.

To all whom it may concern:

Be it known that I, FRANK THILL, a citizen of Luxemburg, and a resident of the city of New York, Long Island city, borough of Queens, in the county of Queens and State of New York, have invented a new and Improved Window-Seal Strip, of which the following is a full, clear, and exact description.

This invention relates to window seal strips, an object of the invention being to provide a strip which may be secured to the horizontal rail of one of a pair of sliding sashes and which will be held against the glass or pane of the other sash so as to close the opening between the sashes when one of the sashes is raised and prevent the passage of mosquitoes, flies and the like through the space between the sashes.

In the use of ordinary screens, one of the sashes is moved, and usually the lower sash, so as to provide space for the screen below the same. When this is done an opening is left between the sashes through which mosquitoes, flies and the like enter the room, and it is the purpose of my invention to provide a strip which is especially designed to be secured to the lower horizontal rail of the upper sash and which has a flexible strip elastically or resiliently held against the lower sash so as to effectually close the opening between the sashes and prevent entrance of mosquitoes, flies, etc.

With these and other objects in view, the invention consists in certain novel features of construction and combinations and arrangements of parts, which will be more fully hereinafter described and pointed out in the claims.

In the accompanying drawings—

Figure 1 is a view in longitudinal section through a pair of sliding sashes illustrating my improved strip in operative position, the view being taken in section on the line 1—1 of Figure 2;

Figure 2 is a fragmentary view in section on the line 2—2 of Figure 1.

1 represents a window frame having the ordinary upper and lower sliding sashes 2 and 3, respectively. 4 represents a screen placed in the window frame under the lower sash.

5 represents my improved window seal

strip which is composed of spring metal, preferably thin steel. This strip is bent forming a clamp 6 in which a flexible strip 7 is secured. This strip 7 may be of rubber or any other analogous material and it is designed to engage the glass or pane 8 of sash 3.

The metal portion of the strip 5 is so shaped as to provide an upwardly projecting flange 9 secured by tacks or other suitable securing devices 10 to the forward face of the lower horizontal rail 11 of upper sash 2.

Between the flange 9 and the clamp 6 the metal strip is bowed forwardly, as shown at 12, so as to provide a spring which functions to press the flexible strip 7 against the glass 8 and also functions to allow a certain bending action of the strip as a whole when the meeting rails of the sashes are brought together so as not to interfere with the closing of the window.

It will thus be noted that I not only provide a device which holds a flexible strip between the window sashes to close the opening between the sashes but I also provide resilient means constituting an integral portion of the metal strip which ensures proper engagement with the window pane and allows of a certain amount of movement to properly accommodate the device to its position or positions.

The strip may be made in suitable lengths and the flexible strip 7 may be cut as desired so as to exactly conform to the shape of the window sash with which it is to engage, as shown clearly in Figure 2.

Various slight changes and alterations might be made in the general form of the parts described without departing from my invention and hence I do not limit myself to the precise details set forth but consider myself at liberty to make such slight changes and alterations as fairly fall within the spirit and scope of the appended claims.

I claim:

1. A window seal strip, including a strip of spring metal having a clamp at its lower portion, a flexible strip secured in said clamp, said metal strip having an upwardly projecting flange adapted to be secured to a window sash, and said metal strip between the flange and the clamp body bowed forming a spring and holding the clamp.

portion normally spaced from the sash to which it is secured.

2. A strip of the character described, comprising a metal strip and a flexible strip, the metal strip bent upon itself at its lower edge forming a clamp in which the flexible strip is secured and at its upper portion

bowed forwardly and then located in a straight line whereby the strip constitutes a spring or resilient member to exert pressure on the flexible strip and holding the clamp portion normally spaced from the sash to which it is secured. 10

FRANK THILL.
